ADJUSTABLE PISTON

Kenneth A. Clark, Waterloo, Iowa, assignor of
one-third to Harold O. Roepe and one-third to
Nels C. Madsen, both of Waterloo, Iowa

Application December 4, 1933, Serial No. 700,772

3 Claims. (Cl. 309—12)

My invention relates to improvements in pistons for internal combustion engines, and the object of my improvements is to furnish a sectional piston of a simple and inexpensive construction, and which has its elements so relatively arranged as to be capable of their radial as also their longitudinal adjustment.

In this class of pistons a piston must have small clearance in a cylinder in order to maintain compression without leakage of gas while in combustion or oil passage by the piston other than for suitable lubrication, or intrusion into the combustion chamber of crank-case oil. Piston-slap must be avoided, and my invention prevents this as the skirt element of the piston is constructed and adjustable for this purpose. The skirt is thus adapted to the cylinder wall for proper coaction notwithstanding wear of either or both.

A single means of adjustment for the above purpose also is effective in extending the piston length as may be necessary at times for different engines. My invention further saves weight of many or complicated parts such as are known in some other pistons.

I have in my invention accomplished all of the above objects in actual reduction to practice and by the means which are hereinafter described and claimed, and which are illustrated in the accompanying drawing, in which Figs. 1 and 2 are central longitudinal sections of my improved assembled piston taken at approximately a right angle apart. Fig. 3 is a central longitudinal section of the skirt element alone. Fig. 4 is a top plan of said skirt element alone, and Fig. 5 is a top plan of one of the shims.

The body or head part of my piston 1 may have a number of ring grooves 2 to receive the usual piston rings not shown, and its body has a diminished portion 1' whose medial zone is cylindrical, and which has at top and bottom, frusto conical outer annular faces 13 and 14 respectively. The body 1 has the usual aligned pair of wrist-pin bosses 6 with bearing seats 6' for a wrist-pin not shown. A lubrication passage 11 is provided in each boss.

The skirt element 12 is longitudinally hollow and its inner wall beginning at the top as illustrated has interiorly a coned part 15 to fit slidably about the coned face 13 of the body 1, having below a cylindrical inner face to fit likewise upon the medial outer face of the body part 1', and having below the latter face a fitting coned face 16 to fit also slidably upon the said coned face 14, an annular cylindrical inner face 17 being just be-

low the coned face 16. The lower end of the skirt has a narrow inner flange interrupted oppositely by inwardly extending radial bosses 8 having tops in the same diametrical plane and provided with interiorly threaded holes 8' alined longitudinally with interiorly threaded sockets 7 in downward extensions 5' of said wrist-pin bosses 5, the lower ends of said extensions being spaced apart at 10 from the said flanged bosses 8. Headed screws 9 are seated in the unthreaded seats 7 and 8' for 10 securing the skirt 12 in longitudinally adjusted positions upon the body part 1'. The skirt 12 has at one side therethrough the inclined split 18, and the piston parts 1 and 12 are of resilient metal, or the skirt has a suitable degree of resiliency, to 15 permit of its expansion or contraction radially as operated upon by the screws 9, as the inclined zones 15 and 16 slide upon the outer fitting like coned zones 13 and 14 of the body, causing by pressure or release of pressure the desired amount 20 of such expansion or contraction of the skirt to cause it to fit closely the inner bore of an inclosing cylinder wall adjustably.

It will be seen that when initially fitting the piston to the cylinder, and the amount of necessary adjustment has been thus ascertained, one or more shims 19 may be seated on the stems of the screws 9 to fill the interspaces of the bosses 8 and the lower ends of the extensions 5', as the shims have holes 20 for that purpose. These 25 shims filling the cavities 10 between the bosses 8 and the extensions 5' secure the skirt in its adjusted position tightly without possibility of looseness of the skirt upon the body 1. The cylindrical fit at 1' between the body and skirt is such as 30 to prevent any side play of the skirt in any adjusted position of the coned fittings.

I claim:

1. A headed hollow piston comprising a head part and a singly longitudinally split resilient skirt part having longitudinally spaced conical faces slidably associated with complementary faces on the head part, the conical faces on each part being connected by a cylindrical face, means for securing said parts in a desired longitudinal adjustment upon each other to effect also a desired radial expansion or contraction of the skirt part.

2. A headed hollow piston comprising metal sections consisting of a hollow head part and a longitudinally singly obliquely split resilient skirt part mounted thereon, said parts having cylindrical medial zones and having complementary coned fitting zones at the ends of the medial zones, and said parts having spaced apertured portions,

adjustable fastening means mounted in said portions and actuatable to slidably move the skirt longitudinally upon the head part, to effect expansion or contraction of the skirt part radially while the latter is moving to or fro upon the head part longitudinally.

3. A headed hollow piston comprising metal sections consisting of a hollow head part and a longitudinally obliquely singly split resilient skirt part mounted thereon, said parts having cylindrical medial zones and having complementary coned

fitting zones at the ends of the medial zones, and said parts having apertured portions, screw fastenings in said portions to adjust the extent of expansion or contraction of the skirt by sliding the skirt upon said head part, said portions being spaced apart, and an apertured shim or shims mounted on each screw to hold the skirt rigidly in place in the desired position of adjustment longitudinally upon the head part.
